UNITED STATES PATENT OFFICE

2,517,857

DRIER

Thomas Evans, Saginaw, Mich., assignor to Baker Perkins Inc., Saginaw, Mich., a corporation of New York

Application July 11, 1946, Serial No. 682,845

3 Claims. (Cl. 259—109)

1

This invention pertains to drying apparatus for converting various fluid materials into powder or granular form.

More particularly, it pertains to means for application of heat to the primary material, for the removal of vapors that are thereby created, and for the coincidental stirring, rotating, overturning, linear flow and cascading of the mass of material while it is being processed.

An object of my invention is to provide a drier of such type wherein the working chamber or space is in the form of an annular chamber, elongated and disposed with its central axis substantially horizontal and having its outer shell stationary and its inner shell rotatable. The improvement also comprises means for continually heating or cooling the material in the chamber, as may be required, both from the outside, as by means of steam jackets on the outer shell, and by steam circulation through the inner shell.

Another object is to provide such a drum assembly with scraper and agitator means for both outer and inner drum surfaces located in the working space between the drums and revolvable in the opposite direction to the rotation of the inner drum.

An object is to provide such a drier with improved power driven rotating drums and scrapers that are simple, compact, relatively inexpensive to manufacture and to maintain, and unusually effective in respect to efficiency of heat transfer to or from the material and also in respect to the rapid and uniform conversion of the prime material from a liquid or more or less viscous state to a state of uniform granulated or dry pulverized character.

Another object is to provide a unique coaxial drum and agitator arrangement, and a driving mechanism therefor, that shall be durable through a long life of service, under heavy duty.

With the foregoing and certain other objects in view which will appear later in the specifications, my invention comprises the devices and combinations of elements and assemblies which will now be described and such modifications thereof as properly are included in the scope and spirit of the appended claims, forming a part of these specifications.

Reference may be had to the accompanying drawings wherein the same letters of reference designate the same or similar parts throughout the several views.

In the drawings:

Fig. 1 is a vertical longitudinal sectional view, partly broken away, showing a preferred arrangement.

2

ment of the principal cooperating elements and assemblies that comprise a drier embodying my invention;

Fig. 2 is a side view of the agitator scraper assembly, from which the driving mechanism is omitted;

Fig. 3 is a diagrammatic longitudinal sectional view of the bearing elements of Fig. 2, without the blades and their supporting lugs;

10 Figs. 4, 5, 6, 7, are transverse sectional views taken on lines 4, 5, 6, 7, respectively, in Fig. 2, to illustrate the fixed angularly displaced relationship that each blade section bears to the others.

15 My improved drier comprises, in general, three principal cooperating parts, Fig. 1. There is a stationary outer drum assembly; a rotatable inner drum assembly, and what may be termed a scraper-agitator assembly, the latter doing its work while rotating in the annular space S that exists in shell 1 of the stationary outer drum.

All three assemblies are coaxial. The material to be treated, for instance, by drying with steam or the like, is contained in the annular space S during the processing operation. The inner drum is rotatable, say, in the counter-clockwise sense, Figs. 4 to 7. The scraper-agitator is rotatable clockwise around the revolving inner drum, like a wheel hub that runs on a rotating hollow axle.

20 30 Auxiliary parts of my improvement pertain to compact simplified mountings and driving means for the principal parts alluded to above.

The outer drum assembly comprises a hollow elongated substantially horizontal cylindrical shell 1, supported in fixed position. It is provided with a suitable heat-transfer jacket 2 and has a charging inlet 3 and a discharge outlet 4 and an outlet 5 for vapor released from the material to vacuum or atmosphere.

40 The outer drum has end walls 6 that project upwardly from the base of the machine. Each end wall is provided with a central stuffing box 7 including a fluid-tight packing and a gland, preferably arranged as shown in Fig. 1.

45 The inner drum assembly consists of a hollow rotatable shell 8 contained within the stationary outer drum. The inner shell is somewhat shorter than the outer stationary drum and is coaxial therewith. End spaces 9 are thus provided between the heads 10, 10 of the inner drum and the end walls 6, 6 of the outer drum, the purpose of which is to receive rotatable flanges 11 of the scraper-agitator assembly, as will be described presently.

50 55 Each head 10 of the inner drum has an axially

extended externally packed quill shaft portion 12. Through one of them a heating medium such as steam can be supplied to the drum; and condensate can be withdrawn through the other.

The quill shaft is mounted to rotate in bearing sleeves 13 provided in a tubular axle 14 of the scraper-agitator assembly, which will now be described.

The scraper-agitator assembly which is illustrated in a preferred form in Figs. 2 to 7, bears a general resemblance to the rotating member of a squirrel cage or to the knives of a lawn mower, but it is of different design, construction, arrangement and mode of operation.

My scraper-agitator assembly comprises two tubular axles spaced apart endwise, as indicated at 16, Fig. 3, with the plate flanges 11, 11 on their inner ends.

A suitable number of rotatable sleeves 15 are spaced apart between the opposed flanges 11, as shown. The sleeves 15 are in fact rotary bearing rings with smooth inner surfaces that ride around upon the external face of the inner drum shell 8 as a bearing, Fig. 4, while the drum itself is rotating in the opposite sense.

As shown in Figs. 2 and 3, the plate flanges 11 on the tubular axles 14 and the intermediate sleeves 15 divide the working length 16 of the scraper-agitator assembly into four sections designated by the broken lines 4, 5, 6, 7. Each section may be regarded as a squirrel-cage arrangement comprising three longitudinally disposed and peripherally spaced blades; one blade 17 is adapted to scrape material from the outside surface of the inner drum; another blade 18 scrapes the interior surface of the outer drum; and the third askew blade 19 is adapted to mix and stir and lift the material during the drying operation while also moving it progressively from the ends of the scraper-agitator assembly toward its mid-length. Blade 19 need not be a scraping blade.

The ends of the three blades are supported by lugs 20 which are fixed to the flanges 11 of the axles 14. The ends of other blades are carried by lugs that are fixed to the rotatable sleeves 15, as shown in Fig. 2, and Figs. 4 to 7. The outer ends of the blades (in sections 4 and 7) are supported by the flange plates 11 of the tubular axles 14.

Referring now more in detail to Figs. 4 to 7, which are end views, somewhat enlarged, taken in planes indicated by lines 4, 5, 6, 7, Fig. 2; there is shown in cross-section, at Figs. 5 and 6, the inner revolving drum and also the rotatable sleeves 15 that slide rotatably as bearings upon the drum and carry the scraping and mixing blades 17, 18, 19. The several views of this series are arranged in the regular order indicated in Fig. 2. They illustrate a preferred circularly staggered arrangement of the several blade-carrying sections relatively to each other, adapted to give smooth action with a uniform torque.

The two tubular axles 14, 14 at the ends of the blade assembly are rotatably mounted in liquid-tight packing boxes 21 mounted in the opposite end walls 6, 6 of the outer drum, as shown in Fig. 1. The outer ends of axles 14, 14 are supported in outboard journal bearings 22, 22. Drive gears 23, 23 are fixed on the axles 14 intermediate each stuffing box 21 and the outboard bearing 22. Meshing with these gears 23 are pinions 24, 24, which are fixed to a single master shaft 25 that is driven from any suitable source of power such as that represented by the primary chain sprocket 26.

Thus, sprocket 26 serves to rotate the two 75

tubular axles 14, 14 and their opposed flanges 11, 11, thereby actuating all the scraping and mixing and stirring blades simultaneously and so preventing material from adhering to the inner end walls 6 of the outer drum or to its inner cylindrical surface 1. Also, the outer surface 8 of the inner drum is kept scraped clean. In addition all material in the annular space S between the two drums is mixed and urged toward the lower middle outlet 4.

The finished granular or powdery dry product is discharged through the lower outlet 4 after the desired degree of dryness and of granulating or powdering has been attained.

In operation, the drier is charged with the fluid, which is to be reduced from a wet state to dry granules or powder, by pouring it into the outer drum through the charging inlet 3, the quantity being preferably sufficient to fill the annular space S between the drums up to about the level of the axis. The inlet 3 is then closed and, in case of operation by vacuum, the vapor outlet 5 is put into communication with a space which is kept at lower than atmospheric pressure.

25 The primary sprocket 26 is then put in rotation. It turns the master shaft 25 and pinions 24, 24. The drive gears 23, 23 rotate the tubular axles 14 and their flanges 11, thereby revolving the scraper-agitator assembly, Fig. 2, in, say, a direction indicated by the curved arrows in Figs. 4 to 7 inclusive. At the same time the master shaft 25 rotates a drive sprocket 27 and a driven sprocket 28. These sprockets are connected by a drive chain, omitted from Fig. 1 for the sake of clearness. The sprocket 28 turns the inner drum by means of one of the quill shafts 12, in the direction indicated by the curved arrow near the numeral 15 in Fig. 1, counter to the revolution of the scraping and agitating blades 17, 18, 19.

40 If the operation being considered is one wherein vapor is being driven off from a liquid or other fluid material for the purpose of recovering the residual ingredients in dry granular or powder form, or in a fragmented partly dried state, the outer drum is heated by application of steam or the like to shell 1, in known manner.

Similarly, the interior of shell 8 is heated by supplying steam; for example, through the inlet conduit 29 of quill shaft 12.

50 Condensate escapes from shell 1 through the outlet 30 of the other quill shaft, being picked up through a suitable nozzle 31.

While the vapors are being removed and the material in space S is changing from its initial 55 condition to its final condition, the blades 17, 18, 19 in each of the sets 4, 5, 6, 7, Fig. 4, are, respectively, scraping the outer face of the inner rotating drum clean with each turn of the drum; scraping the inner face of the outer stationary drum and agitating mixing, dipping, and pouring the material while urging it toward the mid-length of the hot shells of the drums. Heat transference is carried on efficiently by this arrangement by keeping the walls clean and by

60 pouring the material from above onto the hot top of the inner drum as the blades drain in their top position.

In the granulating stage the particles fall down onto the hot shell 8 and take up an added quantity of heat by direct contact with the shell, so that drying can be quickly completed in a very thorough manner, as is done in certain types of earlier driers used in the final evaporating step of manufacture of common salt and similar material.

If desired a number of driers such as described above may be connected together in series and known in the art as multiple effect evaporators; using the vapor discharge from the outlet 5 as the live heating agent for the next evaporating and drying unit.

Having described my invention, what I claim as my invention and desire to secure by Letters Patent is:

1. In a drier of the character described where-
in a stationary outer drum surrounds a coaxial
revolvable inner drum; a scraper-agitator as-
sembly revolvable in the space between said
drums; a series of spaced bearing rings slid-
ingly rotatable around said revolvable inner
drum; peripherally spaced lugs on said rings;
blades on said lugs of which at least one is a
scraping blade adapted to operatively engage the
exterior surface of the said revolvable inner
drum; another scraping blade similarly adapted
to engage the interior surface of the said sta-
tionary outer drum; and a mixing blade set
askew; operative means for rotating the inner
drum in one direction and the scraper-agitator
mechanism simultaneously in the opposite di-
rection.

2. A scraper agitator for a drier comprising tu-
bular axles spaced apart endwise, having plate

flanges on their inner ends; rotatable sleeves
spaced apart between said flanges; lugs extend-
ing outwardly from said plate flanges and said
sleeves; blades disposed longitudinally and stag-
gered circularly on said lugs, in sections; each
section comprising an outside surface scraper
blade, an inside surface scraper blade, and an
askew mixer blade.

3. Scraper-agitator structure as claimed in
claim 2, wherein the mixer blade of each section
is arranged peripherally relatively to like blades
of adjacent sections so as to present an askew
arrangement of said blades adapted to urge ma-
terial from the ends of the scraper-agitator as-
sembly toward its mid-length.
